CLAIM

The ornamental design for a vacuum cleaner, as shown
and described.

DESCRIPTION

FIG. 1 is a top perspective view of a vacuum cleaner,
showing my new design, shown with the storage com-
partment cover removed;FIG. 2 is a perspective view of the vacuum cleaner with
the storage compartment cover in place and with a hose
attached;FIG. 3 is a perspective view of the vacuum cleaner as it
appears when ready for storage;

FIG. 4 is a rear perspective view thereof;

FIG. 5 is a bottom plan view thereof.

The conventional vacuum hose is shown fragmentarily
in FIG. 2 for ease of illustration.Fig.1
